John Sebold

By his Attorney Fred C. Fischer.

UNITED STATES PATENT OFFICE.

JOHN SEBOLD, OF NEWARK, NEW JERSEY.

GAS HEATER.

1,402,183.

Specification of Letters Patent.

Patented Jan. 3, 1922.

Application filed February 12, 1921. Serial No. 444,503.

To all whom it may concern:

Be it known that I, JOHN SEBOLD, a citizen of the United States, residing in Newark, in the county of Essex and State of 5 New Jersey, have invented certain new and useful Improvements in Gas Heaters, of which the following is a specification.

The principal purpose of the present invention is to produce a gas heater having 10 means by which the shape of the flame can be controlled and altered as desired from a relatively low, broad expanse to a high, thin blast, as best suited for the work it is to do.

Another object is to provide a burner 15 built on lines demonstrated by experience to produce the best attainable results.

A further purpose is in the provision of 20 means, forming a part of the heater, for conveniently and efficiently supporting various articles used in connection therewith, as well as sundry work parts, so that the same will receive the heat in an effective manner.

These and other analogous objects, becoming apparent as the description proceeds, 25 are attained by the novel construction, combination and arrangement of parts and the use of thermic principles hereinafter described and shown in the annexed drawings, forming an essential part of this disclosure, and in which:—

Figure 1 is a top plan view of a heater made in accordance with the invention.

Figure 2 is a front elevational view of the 35 same, indicating in broken lines one of its applications.

Figure 3 is an enlarged fragmentary partial elevational, partial sectional view of the burner inlet.

Figure 4 is a bottom plan view thereof.

Figure 5 is a perspective view of the air inlet central element.

Figure 6 is a diagrammatical plan of the 40 heater showing the application of a work support attachment.

Figure 7 is a similar view showing another attachment in the form of an oven or furnace.

Figure 8 is an end view of the same.

Figure 9 is a side elevational view of the 45 upper part of the heater, partially in section and showing it in use as heating a plate.

Stated in general terms the invention comprises a relatively heavy base from which rises a number of posts, supporting a cup having a central opening through which 55 the heat ascends from a burner tube below.

This burner tube is secured centrally of the base, has a gas inlet nipple, and an air mixing chamber thereabove from which the burner tube rises.

60

Two sets of air inlet passages are provided in the mixing chamber, one being below and the other above the gas inlet nozzle and either set may be used by shifting an enveloping shutter encircling the 65 wall of the mixing chamber and having a support arm slidably engaging one of the posts.

Referring now more particularly to the drawings, the numeral 15, designates a circular base of considerable size and weight, 70 made preferably of cast or malleable iron, with a central raised portion 15' having a hub-like projection 16 and three equally spaced bosses 17 arranged in a triangle 75 upon the thickened portions of the base.

These bosses are fitted to have fixedly engaged therein the lower ends of straight cylindrical posts or rods 18, the upper ends of which are similarly fixed in like bosses 80 19 integrally formed upon the convex exterior of a hollow cup 20, so as to firmly support the same and whatever it may contain.

A circular opening 21 is formed in the 85 bottom of the cup, in register with the projection 16 and the interior of the cup is provided with a plurality of triangularly sectional ribs 22 extending from points near the center opening up to its edge and passing 90 over it forming raised narrow projections 23 above its surface.

The base projection 16 is drilled transversely and has secured in the opening thus made a pipe 25 extending horizontally outward and adapted to receive over it a flexible hose (not shown) connecting with a supply of gas in a manner well understood.

The same projection is also drilled and 100 tapped vertically to receive a screw threaded plug 26, its tapered tip 27 extending into

a mixing chamber 28 its cylindrical wall having two annular rows of perforations 30 and 32, respectively above and below the tip 27, while in the bottom wall is another row of smaller perforations 31, all for the admission of air at atmospheric pressure, see Figs. 3 and 4.

Gas from the inlet pipe 25 enters the bottom of the intersecting opening and passes upward through a gradually contracted or conical axial passage 33 in the plug 26 into the chamber 28 where it is mixed with air, the combined gas and air rising from the mixing chamber through the burner tube 34 fixed in it and extending nearly to the bottom of the cup 20, in such manner that when the issuing gases are ignited the flame enters the opening 21, producing an intense heat within the cup.

The shape of the flame and its intensity depends very considerably upon whether air is admitted through the openings 30 or 32; if the upper row 30 be covered, the flame extends to a greater height and does not tend to spread to the same extent as when the lower row be covered and the upper apertures opened.

These openings are controlled by a cylindrical shutter 35 fitted to slide upon the wall of the chamber 28, so as to fully cover either row of openings 30 or 32 and also partially both rows, at one time if desired.

Formed with the shutter is an arm 36 leading to a sleeve 37 slidably engaged on one of the posts, adhering by frictional contact sufficiently to remain in adjustment except when it is desired to move the same in regulating the air inlet.

Extending outwardly from the marginal edge of the cup 20 is a horizontal flat projection 40 containing an enclosed elongated slot 41, while from the edge directly opposite are a pair of projections 42 having between them an open space 43.

These elements furnish means for securing an oblong receptacle 44 over the top of the cup 20, oven, muffle or furnace 44, having a flat bottom edge resting on the cup and passing over its arched cover 45 is a strap 46, one of its out turned ends being engaged in the slot 41 while the opposite end, provided with lateral projection 47, is entered below the elements 42 holding the device secure.

If preferred one or both of the end walls 48 of the device may be engaged by hinges and held when closed over the roof or cover element 45. (See Figs. 7 and 8.)

Obviously metal straps of varying lengths may be used in connection with the projections for securing articles in position to receive heat; however if the articles be flat and of size compatible with the diameter of the cup 20, as indicated by the disk 52, they

may be merely disposed on the projection 23 as shown in Fig. 9.

Attention is called to the broken lines in Fig. 2, the same representing an ordinary melting ladle, its bowl 55 resting upon the ribs 22, and the handle 56 extending outwardly as shown.

These examples clearly show the purpose of the interior lugs 22 and projections 23, which is to permit the full escape of the products of combustion and avoid clogging or smoking, at the same time bringing the articles as near as possible within the area of combustion.

Figures 1 and 6 show another simple but efficient means for supporting relatively long articles, such for instance as a soldering iron, in proper relation to the source of heat.

At a point remote from the projections 40 and 42, is a single width level surface lug 58 formed with an elongated transverse, bar-like head 59, between which and the margin of the cup are recesses 60.

A rod or wire 62 is formed with convergently inclined arms 63, their free ends being adapted to engage over the bar element 59, while curved extensions 64 pass downward in the recesses 60 and make contact with the exterior of the cup in an obvious manner and it will be clearly apparent this supported element may be applied or removed in an easy and expeditious manner.

While certain preferred embodiments of this device have been shown and described, it will be understood that changes in the form, arrangements, proportions, sizes and details thereof may be made without departing from the scope of the invention as defined in the appended claims.

Having thus described my invention, what I desire to secure by Letters Patent and claims is:—

1. A Bunsen burner having a conical gas inlet, a cylindrical mixing chamber having in its cylindrical wall a series of air inlets arranged respectively before and behind the point of gas discharge from said inlet and a perforate wall at one end thereof, and means for adjustably and selectively controlling either or both series of air inlets in the cylindrical wall of the mixing chamber.

2. A burner comprising a cylindrical mixing chamber having in its cylindrical wall spaced annular rows of perforations and a perforate wall at one end thereof, a burner tube leading from said chamber, a gas inlet tip terminating at a point within said chamber midway between the rows of perforations, and a shutter controlling the air passages in either row of perforations in the cylindrical wall of the mixing chamber.

3. A burner comprising a cylindrical mixing chamber having a burner tube at one end and a perforate wall at the other, there

being two spaced annular rows of perforations in the circular walls of the chamber, a gas inlet having a conical passage terminating in a tip midway between the mentioned rows of perforations, a shutter slideable over said chamber adapted to close either row of perforations in the cylindrical wall of the mixing chamber partially or

wholly, and means for holding said shutter in adjustment.

This specification signed and witnessed this tenth day of February, 1921.

JOHN SEBOLD.
